UNITED STATES PATENT OFFICE.

FRANKLIN E. ABBOTT, OF BUFFALO, NEW YORK, ASSIGNOR TO LACKAWANNA STEEL COMPANY, OF LACKAWANNA, NEW YORK, A CORPORATION OF NEW YORK.

TIE PLATE.

1,425,310.

Specification of Letters Patent. Patented Aug. 8, 1922.

Original application filed May 26, 1911, Serial No. 629,654. Patent No. 1,178,200, dated April 4, 1916. Divided and this application filed March 10, 1916, Serial No. 83,220. Renewed January 13, 1922. Serial No. 529,095.

To all whom it may concern:

Be it known that I, FRANKLIN E. ABBOTT, a citizen of the United States, residing at Buffalo, in the county of Erie and State of New York, have invented new and useful Improvements in Tie Plates, of which the following is a specification.

My invention relates to tie-plates for railways characterized by a hook-shoulder arranged to engage with the rail-flange and consists in providing a second shoulder for engaging with the opposite rail flange.

I have heretofore invented an improvement in hook-shoulder tie-plates which consists in forming and proportioning the hook-shoulder so that its overhang shall be spaced a small distance from the upper surface of the rail flange, whereby the great security of the hook fastening is obtained without objectionable rigidity, and freedom of wave motion is permitted, with greatly reduced disturbance of the spikes and of the road-bed. Tie-plates provided with my peculiar hook-shoulder and with an ordinary straight shoulder for engaging with the opposite rail flange have gone largely into use of late, particularly for difficult locations, where security in the rail fastenings is important and accident would have serious consequences.

I believe such tie plate to be new and I have broadly claimed the same in my application which resulted in Patent No. 1,178,200, April 4, 1916.

My present invention consists in a tie-plate whereby much greater security is obtained, and this is accomplished by providing the tie-plate with two hook-shoulders, one integral as before, and the other consisting of an integral shoulder without a hook and of a detachable hook, or clip, fitted to the second shoulder and secured in position thereon. Both shoulders are spaced from the flange.

My invention is fully shown in the drawing herewith in which the reference numerals of this description are used to indicate the corresponding parts in all the views. Figs. 1 and 2 show in plan and side elevation a desirable form of tie-plate embodying my present invention. Figs. 3 and 4 are corresponding views of the "clip" or detachable hook portion. Figs. 5 and 6 show the tie-plate applied respectively to wooden and to

metal ties. Fig. 7 is an end elevation of a metal tie and Fig. 8 shows the short form of 55 clip in plan.

In the figures 1 indicates the tie-plate provided with two integral shoulders, one the integral hook-shoulder 2 the subject matter of my former application and the other the 60 clip shoulder 3, adapted to receive the detachable clip 4, provided with the hook, or clip-hook, 5.

This second shoulder is formed as a holder to receive and firmly to sustain the clip so 65 that the clip-hook may operate to engage with the rail base on the side opposite the integral shoulder and cooperate with the latter to retain the rail in place with great security. To that end the second, or straight, 70 shoulder may be of any desired form that will firmly engage with the groove in the clip, but preferably as here shown substantially of dove-tail construction, having one or more upper flanges or enlargements 7, so 75 that the upper part is wider than the neck. The particular form here shown of outwardly and upwardly curved flanges is desirable for such shape of shoulder is easy to roll and requires the minimum of metal. The clip 4 80 is correspondingly formed with claws 11 forming a groove 12 substantially to fit the dove-tail shoulder, both the shoulder and clip being of uniform size from end to end so that the clip fits the shoulder snugly, but 85 yet may easily be slipped into place thereon after the rail has been set in position on the bed 14 between the two shoulders.

The rail is then firmly and positively secured in place by the two hooks, of which 90 the clip-hook is maintained firmly in place by its peculiarly formed shoulder against all possibility of displacement by any force that may be exerted thereon by the rail. And by this construction of tie-plate the fastenings 95 between the rail and the tie-plate are entirely independent of the fastenings between the plate and the tie. The latter are not in contact with the rail and therefore are not disturbed or loosened by direct strain thereon of the rail during the wave motion, and, owing to the space between the hooks and the rail flanges, the indirect effect of the wave motion on the spikes is trifling.

There exists however the possibility of the 105 clip slipping off gradually and longitudi-

nally due to vibration. To counteract this some retaining means must be provided such as the spike 16 through the spike holes 17 and in clip and shoulder as shown in Fig. 5 and Figs. 1 and 3, or the special bolt 18 and nut of Fig. 6.

The edges of the tie-plate outside of the shoulder may be made thinner and lighter to save metal, but the center heavier and thicker to resist the stresses and to afford a good bed for the rail. The tie-plates are preferably balanced, that is of equal width on each side of the central longitudinal axis of the rail-bed to permit reversal and convenient handling. The plates may be longer for wooden ties and shorter for metal.

My tie-plate is equally well adapted to both wooden and metal ties. In Fig. 5 the tie-plate is shown in use with wooden ties, secured in place by driven spikes or screw spikes, 22, the latter form of spike being indicated. To carry out the best plan of installing the tie-plates on wooden ties, places of plate bearing should be formed at both ends of the tie, even and flat and exactly in the same plane. When screw spikes are used, it is also desirable and economical to bore holes in the tie therefor and to fasten the plates to the ties in the shop by machines. In Fig. 6 the tie plate is shown secured to a metal tie by bolts or rivets 23; this assembling may also be more conveniently done at the factory than in the field. The ties whether wood or metal, thus fitted with the tie-plates, are then carried to the place of use, where they are placed in the road-bed, the rails then set in position and securely fastened to the tie-plates and the ties by putting the clips in place on the clip shoulders.

Furthermore my new tie-plate permits the convenient replacing of ties with the track in position. A single tie may be removed, and a new one with the tie-plates attached easily be substituted, for there is sufficient space between the two shoulders to permit the rail to be set in position on the tie-plates and then the integral hooks adjusted to engage with both rails. The clips are then easily put in place on their shoulders and there fastened, completing the holding arrangement.

It will be understood that I intend to leave a clear space of sufficient size between each hook and the rail-base to permit the free wave motion as above described and not so large but that at each upward movement of the rail it will engage with the hook to be held down in place and prevented from upsetting. A space of from $\frac{1}{2}$ to about $\frac{1}{4}$ inch is recommended, not above about $\frac{1}{8}$ inch. My present invention is not limited to such space, but the tie-plate here described and claimed may be used with a space under one hook, or under both, or

under neither, that is the hooks may fit the flanges tight if anyone wishes so to use them, without departing from my present invention.

Nor do I propose to limit myself to having one hook or the other on the inside but either the integral or detachable hook may be arranged inside or out as most convenient. I so calculate the metal that the clip hook is substantially as strong as the integral, but nevertheless I prefer to arrange the integral hooks on the outside where the greater strain comes. In case of only one hook shoulder, with a parallel straight shoulder on the opposite side of the rail, my form of detachable clip shoulder may be used, but I should prefer the integral hook shoulder for such a form of tie-plate.

My tie-plates are preferably made by rolling but they may be cast or forged in whole or in part, or certain parts bent to shape more or less by forging or bull-dozing. The integral shoulders may extend the full length of the tie-plates and the hooks thereon extend from end to end of the shoulder as described in my said application but I prefer to make said hooks shorter as here shown. The clip-shoulders and clips may also be equal in length to the length of the tie-plate, and it is preferred to so form the clip-shoulders, but the clip hooks may be shorter and preferably substantially equal in length and extent of engagement with the rail flange to the integral hooks, when they are short.

Having described my invention I claim:

1. A tie-plate comprising a base, parallel shoulders on the upper surface thereof, one shoulder having a hook adapted to overhang the edge of the rail-flange, the other shoulder having a wider upper portion and a narrower neck there below, and a separable clip having a groove to fit the second shoulder and a hook to overhang the adjacent flange edge of the rail.

2. A tie-plate comprising a base and parallel shoulders on the upper surface thereof, both shoulders being provided with hooks arranged to overhang the rail-flange edge and slightly spaced therefrom, one hook being integral with its shoulder and the other separable therefrom.

3. A tie-plate comprising a base and integral, parallel shoulders on the upper surface thereof, both shoulders being provided with hooks arranged to extend over the rail-flange edges and spaced therefrom sufficiently to permit free wave motion, but the space being small enough to insure engagement with the hooks at each upward movement of the rail, one hook being integral with its shoulder and the other separable therefrom and means to secure the separable hook on its shoulder.

4. A tie-plate comprising a base, two par-

allel shoulders on the upper surface thereof, said shoulders being spaced a distance more than sufficient to receive the rail base between them, one shoulder having an integral hook overhanging the rail flange, the second shoulder being of uniform structure from end to end with enlargements on its upper portion and a narrower neck below, a separable clip having a hook to overhang the adjacent flange of the rail and claws to engage with said enlargements, said clip being adapted to slip over the second shoulder from one end, and a spike or bolt fitted to holes in the clip and the body of the tie-plate to retain the clip in place against vibration, substantially as shown.

5 5. A tie-plate comprising a base, and parallel integral shoulders on the upper surface thereof, one shoulder having an integral hook substantially shorter than the tie-plate and adapted to overhang the edge of the rail-base and the other shoulder having a detachable hook adapted to overhang the other edge of the rail base.

10 6. A tie-plate comprising a base and two parallel shoulders on the upper surface thereof, said shoulders extending from end to end of the tie-plate, each shoulder being provided with a hook to overhang and engage with the rail edge, both hooks being shorter than their shoulders and one hook being integral with its shoulder and the other separable therefrom.

15 7. A tie-plate for railways comprising a base, two parallel integral shoulders on the upper surface thereof and inclosing between them a bed for the rail, one of said shoulders being provided with a hook to extend over the edge of the rail flange and the shoulder on the opposite side being spaced from the opposite rail flange, and a detachable clip formed to interlock with said second shoulder and provided with a hooked portion to extend over the edge of the adjacent rail flange and means to maintain said clip in place on its shoulder, said clip being adapted to lie entirely above the said rail bed and both of said hooked portions being slightly spaced from the rail flanges to permit a slight upward movement of the rail, but no substantial upward movement and displacement thereof.

20 8. A tie-plate comprising a base provided with an integral hooked shoulder adapted to overlie the edge of the rail flange at one side and with an opposed shoulder on the base, said shoulders being arranged to extend longitudinally and parallel to the rail and a holding clip formed to interlock with the opposed shoulder and adapted to overlie the edge of the adjacent flange, said clip being maintained from lateral and vertical displacement by engagement with its shoulder and means to prevent longitudinal displacement of the clip and both said hooked

shoulder and said clip being slightly spaced from the rail flanges to permit a slight upward movement of the rail, but no substantial upward movement and displacement thereof.

25 9. A tie-plate comprising a base provided with a hooked shoulder adapted to overlie only one edge of the rail flange and with an opposed shoulder, said shoulders being arranged to extend longitudinally and parallel to the rail and a holding clip formed to interlock with said opposed shoulder and adapted to overlie only the edge of the adjacent flange, said clip being maintained from lateral and vertical displacement by engagement with its shoulder and other means to prevent longitudinal displacement of the clip and both said hooked shoulder and said clip being slightly spaced from the rail flanges to permit a slight upward movement of the rail, but no substantial upward movement and displacement thereof.

30 10. A tie-plate comprising a base and opposite shoulders on the upper surface thereof, both shoulders being provided with hooks arranged to overhang the rail flange edge and slightly spaced therefrom, one hook being integral with its shoulder and the other separable therefrom and said separable hook member and the base being formed with registering apertures adapted to receive therein a standard securing spike, substantially as described.

35 11. A tie-plate comprising a base provided with a hooked shoulder adapted to overlie the rail flange at one side, a separable holding clip adapted to be secured on the opposite side of the rail and having a hooked portion adapted to overlie the opposite rail flange, both of said hooked portions being slightly spaced from the rail flanges to permit a slight upward movement of the rail but no substantial upward movement and displacement thereof and said separable clip and base having registering apertures therethrough adapted to receive a standard holding spike, substantially as described.

40 12. A tie-plate comprising a base providing a rail bed on its upper surface and having an integral shoulder thereon, said shoulder being formed with a wider upper portion and a narrower neck therebelow and a separable clip having a groove to fit onto and interlock with the said shoulder and provided with a hook portion to overhang the adjacent edge of the rail and said clip and base being perforated to provide registering apertures adapted to receive a standard securing spike whereby the clip is secured against longitudinal displacement.

45 13. A tie-plate comprising a base providing a rail bed on its upper surface and having an integral shoulder thereon, said shoulder being formed with a wider upper portion and a narrower neck therebelow and a

separable clip having a groove to fit onto and interlock with the said shoulder and provided with a hook portion to overhang the adjacent flange edge of the rail and said 5 clip and base being perforated to provide registering apertures adapted to receive a standard securing spike whereby the clip is secured against longitudinal displacement, and said hook portion being shorter 10 than the tie-plate and slightly spaced from the rail flange to permit a slight upward movement of the rail but no substantial upward movement and displacement thereof.

14. A tie plate comprising a base, parallel shoulders integrally formed on the upper 15 surface thereof and extending longitudinally of and parallel to the rail bed formed therebetween, at least one of the shoulders having a wider upper portion and a narrower neck therebelow and a separable clip having 20 a groove to fit the latter shoulder and a hook portion to overhang the adjacent flange edge of the rail.

In testimony whereof I have signed my name to this specification.

FRANKLIN E. ABBOTT.
